UNITED STATES PATENT OFFICE

ELECTRIC IRON

Application December 7, 1948, Serial No. 63,868

1 Claim.

(Cl. 38—75)

1. The invention relates to electric irons, and more especially to an iron of this type wherein cooling means for the operator and an independent control for the same is embraced with such iron.

The primary object of the invention is the provision of an iron of this character, wherein the crown of its body has counterseated therein an electric motor of the silent type operating a bladed fan, these being located centrally of the said crown, so as to deliver a stream of air only in an upward vertical direction to cool the operator of the iron, not only at the handle area of such iron but for cooling the operator both face and other portions of the body within the range of the air stream while the iron is active or inactive.

Another object of the invention is the provision of an iron of this character, wherein the cooling fan is under direct control of the user of the iron, as the electric power unit for the fan can be turned on or off at will through the medium of a hand switch independently of the turning on or off of the electric heating unit or element of such iron, which control for the last mentioned unit or element being of the usual well known construction, and it is independent of the switch for the electric power unit for the fan.

A further object of the invention is the provision of an iron of this character, wherein the fan and its power unit are readily and easily accessible for the cleaning thereof with dispatch and also these do not interfere with the efficient working of the iron for the purposes intended thereof, the fan and its power unit being located approximately at the middle of the crown of the body of the iron and will not detract from the normal appearance of the latter, while at all times under the direct control of its user.

A still further object of the invention is the provision of an iron of this character, which is simple in construction, thoroughly reliable and efficient in operation, neat and pleasing in appearance, conveniently controlled both in its ironing and cooling operations, possessed of few parts, and inexpensive to manufacture and install, it being devoid of complicated parts, thus susceptible of quick repairs and replacements.

With these and other objects in view the invention consists in the features of construction, combination and arrangement of parts as will be hereinafter more fully described, illustrated in the accompanying drawing, which discloses the preferred embodiment of the invention, and as pointed out in the claims hereunto appended. It is to be understood that changes, variations and modifications may be made in the invention as

shown in the drawing without departing from the spirit of the invention or sacrificing any of its advantages.

Figure 1 is a perspective view of the iron constructed in accordance with the invention.

Figure 2 is a side view, partly broken away.

Figure 3 is a diagrammatic view of the electric circuits and adjuncts thereto.

Similar reference characters indicate corresponding parts throughout the several views in the drawing.

Referring to the drawing in detail, A designates generally an assembled electric iron which may

be of any approved type, including a sole plate 10 having the usual outer ironing surface. This sole plate may be of any suitable and desired kind and for the purposes of illustration only has associated therewith within the body 11 of such iron a suitably insulated and protected heating element, not disclosed in detail, excepting generally at 12. Within the crown 13 of the iron body 14 at a central point of the latter is a circular countersink forming a recess 15 which opens upwardly through the top surface 16 of said crown 13, while counterseated in this recess to snugly and permanently fit the same is a cup-shaped housing or casing 17, which is entirely open at its uppermost portion. Removably mounted over the recess 15 in any suitable manner for covering the upper open portion of the housing or casing 17 is a fully perforated transparent or translucent face plate 18, which on removal give access to the interior of the housing or casing 17.

35 Interiorly of the housing or casing 17 is properly anchored a removable power unit, preferably, a silent rotary electric driving motor 19, of any approved type, having its driving shaft 20 fitted with a bladed fan wheel 21, of a selected kind to be located and operate beneath the face plate 18 for the issuance of a stream of air directly through the perforations 22 in the said face plate 18 in an upward flaring direction only so as to blow cooling air not only onto the hand of the user 40 of the iron when grasping its handle but also upwardly onto the face and body and other adjacent areas thereto of such operator.

The body of the iron A at its heel end 23 is equipped with the usual electrical male plug-in tines 24 for an electric current supply detachable plug, not shown, which is of the usual construction, the tines 24 being connected in an electric circuit 28 with a hand controlled on and off switch, as at 29 to the heating element 12. This switch 45 just mentioned can be located at any accessible

3

exterior point of the iron body 14, and also functions to control the degree of heat by the said element 12 during the use of the iron for the purposes intended thereof.

The electric driving power unit 19 is in an electric circuit 25 which is independent of the heating element circuit before mentioned and has therein a manually operated or controlled on and off switch 26, which is located next to the housing or casing 17 and close to the upper face of the crown 13 for the convenient turning on and off of the motor 19 at will, the circuit 25 being connected to the terminal male plug-in tines 24 heretofore referred to for the current supply detachable plug, not shown, and before mentioned.

The housing or casing 17 has a heat insulating medium 27 about the motor 19, which also functions to silence the latter when in operation.

It is to be understood that in lieu of the perforations 22 there may be substituted spaced slots or equivalents thereof, and the fan 21 when active blows a stream of air in an upwardly direction only at the center of the crown of the body of the iron.

What is claimed is:

An assembly for an electric iron having a sole plate with a confined electric heating element, a

by the time that the first of the new year comes, the
newly-arrived will have had time to get to know
the place, and to make up their minds whether
they will remain or not. The time will be
short, but it will be enough to give them a
chance to do so. The time will be short, but
it will be enough to give them a
chance to do so.

shell rising over the sole plate having a counter-sink approximately at the center of its uppermost surface and a non-heat conductive handle bridging said countersink within the marginal edging of the shell for creating a finger receiving gap immediately beneath the handle to enable hand gripping of the latter directly above said countersink, a perforated cover for said countersink, a rotatable electrically powered bladed fan within the countersink adjacent the cover for forcing atmospheric air upwardly in said gap toward the handle, and means for controlling power to the fan, the power for operating said fan including an electric motor connected with said last named means and positioned in said countersink, and heat insulating means about said motor.
